(57) **CLAIM**

The ornamental design for a medical syringe, as shown and described.

DESCRIPTION

FIG. 1 is a top, front, left perspective view of a medical syringe showing our new design;

FIG. 2 is top, front, left perspective view of the medical syringe, shown in an expanded configuration for clarity of disclosure;

FIG. 3 is a front elevation view of the medical syringe of FIG. 1;

FIG. 4 is a top plan view thereof;

FIG. 5 is a top plan view, shown in a first condition of use; FIG. 6 is a top plan view, shown in a second condition of use;

FIG. 7 is a top plan view, shown in a third condition of use; FIG. 8 is a rear elevation view of the medical syringe of FIG. 1;

FIG. 9 is a bottom plan view thereof;

FIG. 10 is a left elevation view thereof, shown at an enlarged scale for clarity of disclosure; and,

FIG. 11 is a right elevation view thereof, shown at an enlarged scale for clarity of disclosure.

1 Claim, 11 Drawing Sheets
